Primary Examiner — Cathy Anne MacCormac*(74) Attorney, Agent, or Firm* — Thomas A. O'Rourke; Bodner & O'Rourke, LLP(57) **CLAIM**

The ornamental design for a ball, as shown and described.

DESCRIPTION

FIG. 1 is a top view of a ball in accordance with the present invention.

FIG. 2 is a bottom view thereof.

FIG. 3 is a left side view thereof.

FIG. 4 is a rear view thereof.

FIG. 5 is a right side view thereof.

FIG. 6 is a front view thereof; and,

FIG. 7 is a perspective view thereof.
